ARCHED ROOF CONSTRUCTION

Friedrich Förster, Berlin-Wilmersdorf, Germany

Application October 31, 1938, Serial No. 238,034
In Germany November 2, 1937

4 Claims. (Cl. 108—1)

This invention is directed to the making of an arched roof, and more particularly to a light-weight preformed roofing unit.

An object of the invention is to construct a roof covering unit which includes an arch truss construction.

Another object of the invention is to prefabricate roof panels of light weight and great strength.

10 Another object of the invention is to prefabricate a strong and lightweight roof panel which can be used in the construction of portable or permanent buildings, and which, because of its light weight, can be supported upon relatively

15 thin bearing walls.

Generally these objects of the invention are obtained by bending a flexible board into arch form, and holding the board arched by means of a band, extending between opposite ends of the board, 20 this portion of the band acting as the lower chord of a truss. The band can be continued to form diagonal bracing between the board and the chord portion of the band. A truss is thus created with the board acting as the upper chord, 25 and the band providing the lower chord and the diagonals. Vertical posts or struts are added wherever needed. A plurality of boards can be assembled as a prefabricated roofing unit.

The means by which the objects of the invention are obtained is more fully described with reference to the accompanying drawing, in which:

Fig. 1 is a cross-sectional view of a roof, and showing the novel arch truss construction; and 30 Fig. 2 is a bottom plan view of a prefabricated roof panel constructed according to this invention.

In Fig. 1, flexible board 1 is provided with an opening 7 at its midpoint, and an opening 5 adjacent each end. Struts 6 are secured to the lower face of board 1, these struts being located between opening 7 and openings 5, respectively.

A band 3 is stretched across the lower ends of struts 6 and around each end of board 1. The tension in this band pulls the free ends of board 1 down so that the board attains an arched form, and band 3 becomes the lower chord of a truss. Diagonal bracing for the truss is provided by continuing the respective ends of the band downwardly through openings 5, around the lower ends of struts 6, upwardly through hole 7, and then across the upper surface of the board to points intermediate openings 5 and the ends of board 1.

The lower chord and the diagonal bracing are joined to each other and to the lower end of each

strut 6 by any conventional fastening means, such as nails 6a. Likewise, the free ends of the band are lapped at 4 upon the portions of the band continued around the ends of the board, and are fastened to these portions and to board 1 by any conventional means, as nails 4a.

For the purpose of assembling a plurality of boards together to form an arched panel, a cross bar 9 is secured to the underside of the board at its midpoint, and cross-bars 11 are secured adjacent the ends of the board. Bar 9 conveniently becomes a post to which an auxiliary chord 12 is fastened at 9a, this chord 12 extending between bars 11. As shown in Fig. 1, bars 11 act as means for resting the roof upon side walls 10.

The grouping of a plurality of boards together is more fully shown in Fig. 2. A plurality of boards have their ends secured together by transverse members 2, and are secured together at their midpoints by cross-bar 9. Cross-bars 11 20 also act to hold the adjacent boards together.

The two outer boards and the central board are each provided with the truss forming band 3, thus giving the panel an arched form. The panel is completed by cross-bracing 8.

The invention therefore produces a novel arched truss composed of a board, a band, and two struts. This structure is strong, cheap, of light weight, and easily assembled. The board not only functions as the upper chord of the truss, but also as part of the roof covering. A truss made of boards 24 mm. thick, and a steel band 0.9 mm. thick and 24 mm. wide, has a bearing capacity of 100 kg/m². The prefabricated panel of Fig. 2 has additional advantages of lightness because fewer metal bands are used, while at the same time the speed of erecting a roof is increased by the larger panels. Of course any conventional roofing material can be applied over 40 boards 1.

I claim:

1. An arched truss comprising a board having a plurality of longitudinally spaced holes therein, vertical struts fixed to said board, and a band 45 extending through one of said holes adjacent the midpoint of said board, beneath the free ends of said struts, and through other of said holes positioned between said midpoint and the ends of said board, whereby diagonal bracing is formed; 50 said band being continued around and between said ends of said board to form a lower chord, and said chord being tightened to arch said board.
2. A truss as in claim 1, further comprising 55

means for fastening said chord to each of said struts and diagonal bracing, respectively.

3. A truss as in claim 1, further comprising means for fastening the free ends of said band to the outer surface of said board and to the portions of said band between said other holes, respectively, and the ends of said board.

4. An arched truss comprising a board, struts, and a band, said band having its midportion

stretched between the ends of said board and pulling said ends to arch said board, the free ends of said band each being continued around an end of said board to the upper surface thereof, downwardly therethrough, around one of said struts, upwardly through the midpoint of said board, and being anchored to the outer surface of said board.

FRIEDRICH FÖRSTER.
